Patented Apr. 24, 1917.

UNITED STATES PATENT OFFICE.

EARL CASNER, OF CARTHAGE, MISSOURI.

VALVE-GRINDING MECHANISM.

1,224,067.

Specification of Letters Patent. Patented Apr. 24, 1917.

Application filed September 28, 1915. Serial No. 52,998.

To all whom it may concern:

Be it known that I, EARL CASNER, a citizen of the United States, residing at Carthage, in the county of Jasper and State of Missouri, have invented certain new and useful Improvements in Valve-Grinding Mechanism, of which the following is a specification.

This invention relates to valve grinding machines, and has for its object to produce an improved machine or apparatus of this kind that is adapted to be secured to an engine, the valves of which are to be ground, and to simultaneously oscillate the valves while seated to effect a grinding thereof. In the accompanying drawings I have illustrated a machine embodying my invention in its preferred form, the machine therein illustrated being adapted to simultaneously grind four valves of an internal combustion engine of well known type and construction. It will be understood that the invention is not limited in its useful applications to the specific machine illustrated, as the parts thereof may be variously proportioned and arranged to suit the particular engine upon which it is to be used, or the parts may be so adjustably supported as to adapt the machine to use upon engines of different sizes and makes.

Referring to the drawings—

Figure 1 is a front elevation of the machine detached, part of the operating handle being broken away;

Fig. 2 is a top plan view of the machine; Fig. 3 is a side elevation thereof;

Fig. 4 is a vertical section taken on the line IV—IV of Fig. 1;

Fig. 5 is a horizontal section taken on the line V—V of Fig. 4; and

Fig. 6 is a detail perspective view of one of the parts of the machine to be herein-after described.

In the drawings 2 indicates the base or supporting frame adapted to be secured to the frame of the engine the valves of which are to be ground by the machine; and 3 indicates a swinging frame pivotally united with the base frame by pivots 4, and carrying the operative valve grinding parts of the machine. The base frame consists essentially of the parallel end pieces 2', 2' rigidly united in any suitable manner, as by the connecting bar 5. The end pieces 2' are represented as being provided with perfor-

rated lugs 6 adapted to have pass through them screws or clamping devices employed in connecting the machine to the engine.

The swinging frame 3 comprises the parallel end pieces 3', 3', which are respectively united with the end pieces of the base frame 60 by the pivots 4, and a cross plate 7 uniting the end pieces 3', 3'. The forward ends of the end pieces 3', 3', that is, the ends distant from the pivots 4, are shaped to form slide-ways 8 in which is mounted a rack bar 13, to be described. I employ a clamp for uniting the base and swinging frames in working position, as indicated in Figs. 1 and 4. This clamp preferably consists of a bar 9 pivoted at 11, 11 to the end pieces 2' of the base frame, and provided with hooks 10 adapted to engage with the cross plate 7 of the swinging frame when the latter is brought down substantially parallel with the base frame into working position. 75 Springs 12 act upon the clamp to force the hooks thereof into position to engage with the cross plate of the swinging frame and to securely hold the clamp in working position.

19 indicates a top plate supported by pins 80 20 above and parallel with the cross plate 7 of the swinging frame. The upper ends of the pins 20 are screw-threaded and adjusting nuts 22 are mounted on such threaded parts.

85 A series of rotatable spindles 18, there being four of them in the machine being described, are supported in the plates 7 and 19 of the swinging frame, and carry at their lower ends tools for engaging with the valves 90 to be ground. These tools are represented as being heads 23 carrying pins 24, but other forms of tools may be substituted therefor if found desirable. Upon each spindle 18 is secured a pinion 17 with which engages the rack bar 13. The rack bar is connected by a link 16 with an operating lever 14 pivoted in the bracket 15 carried by the swinging frame. It will be readily seen that if the rack bar 13 be reciprocated, 100 through the manipulation of the handle 14, the spindles 18 will be oscillated, and, if the tools which they carry are in proper engagement with the valves of the engine, the latter will be oscillated in their seats and ground. 105

21, 21 indicate coiled springs surrounding the spindles 18 and interposed between the upper plate 19 and the pinions 17. They

operate to hold the valve-engaging tools in engagement with the valves, with yielding force.

Associated with the spindle of each valve grinder is a cam, adapted, during the oscillation of the spindle, to cause it to be longitudinally reciprocated. Most of the valves of engines upon which the machine being described is adapted to operate, are spring-seated, and when the valve-engaging tools are brought into engagement therewith and rotated, the valves are held, by the springs 21, against their seats and in grinding engagement therewith. But by the use of the cam devices referred to, after the spindles have been rotated to a certain extent, as for instance about a revolution and a quarter, the cam devices come into operation and cause the oscillating spindles to be moved, against the action of the springs 21, with the result that the valves are lifted slightly from their seats, permitting any dirt or particles that may have become loosened by grinding to drop away, and also permitting abrasive material to be fed under the valves.

The cam device that I prefer to employ is illustrated in detail in Fig. 6 and consists essentially of a sleeve 25 loosely surrounding the spindle 18 and located between the plate 7 and the pinion 17. The sleeve is provided with a cam 26 and a lug or projection 27. A radially disposed pin 29 is seated in the spindle 18 and is adapted to engage with the upper edge of the sleeve 25. A pin 28 is seated in the plate 7 in position to be engaged by the lug or projection 27 carried by the sleeve.

It will be observed that the means that I employ for periodically moving each spindle longitudinally as it is being oscillated are disposed concentric with the axis of rotation of the spindle, and that one of the parts that effects the longitudinal movement of the spindle, the pin 29 that engages with the cam 25 in the arrangement herein disclosed, is carried directly by the spindle. This arrangement of parts tends to simplicity of construction and compactness in the location of the parts of the machine besides making an apparatus that is not liable to get out of order or become inoperative through long use and wear.

The operation of the machine described is as follows: The base frame 2 is secured to the engine the valves of which are to be ground, in position to permit the heads 23 to engage with the valves when the frame 3 is swung down into working position as indicated in Figs. 1 and 4. It will be understood that the necessary parts of the engine are removed to expose the valves before the grinding machine is put in place. The heads 23 being in engagement with the valves and the frame 3 clamped in working position, the handle 14 is reciprocated and

the spindles 18 oscillated. The several parts of the machine are so proportioned that at each complete reciprocation of the handle each valve spindle is oscillated about a revolution and a half in each direction. Each 70 spring 21 holds its valve spindle down or toward the valve, and the pin 29 which it carries in engagement with the upper edge of the cam sleeve 25. As the sleeve is loosely supported it turns with the spindle until 75 positively arrested by the engagement of the lug 27 with the pin 28. When this takes place the spindle turns relative to the sleeve and the pin 29 rides up the inclined surface of the cam 26, lifting the spindle, compressing the spring 21, and permitting the valve to separate from its seat, as has been described. Upon the reverse movement of the rack bar the rotation of the spindle is reversed and immediately the pin 29 runs 80 down the cam 26, allowing the valve to come to its seat, after which further rotation of the spindle causes the sleeve 25 to turn with it, allowing the valve grinding action to take place.

The force with which the valves are held against their seats during the grinding operation may be varied by means of the adjusting nuts 22, for if they be screwed down upon the pins 20 the springs 21 will be compressed and their tension increased, as will be readily seen.

What I claim is:—

1. In a valve grinding machine, the combination of a supporting frame, a set of rotatable spindles adapted to be connected with the valves to be ground, means for oscillating the spindles, springs acting respectively upon the spindles for holding them in engagement with the valves with yielding force, and means for varying the tension of all the said springs substantially simultaneously and equally at will. 100

2. In a valve grinding machine, the combination of a movable frame having a stationary plate, a movable plate supported parallel with and spaced from the said stationary plate, a set of spindles carrying tools adapted to engage with the valves being ground, supported in the said plates so as to be rotatable therein and also longitudinally movable therein, springs acting upon the said spindles and bearing against the said movable plate adapted to hold the valve-engaging tools to their work with yielding force, and means for adjusting the said movable plate to vary the tension of the said springs. 110

3. In a valve grinding machine, the combination of a rotatable and longitudinally movable spindle adapted to be connected with a valve for grinding it while seated, means for oscillating the spindle, means for holding the spindle against the valve to be ground with yielding force, and means dis- 125 130

- posed concentric with the axis of rotation of the spindle for positively moving the spindle longitudinally as it is being oscillated.
5. 4. In a valve grinding machine, the combination of a rotatable and longitudinally movable spindle adapted to be connected with a valve for grinding it while seated, means for oscillating the spindle, means for holding the spindle against the valve to be ground with yielding force, and means disposed concentric with the axis of rotation of the spindle and arranged to cause the spindle, while being oscillated, to be turned without longitudinal movement thereof, during a portion of its period of oscillation, and to positively cause it to be moved longitudinally during another portion of its oscillation.
10. 5. In a valve grinding machine, the combination of a rotatable spindle carrying a valve-engaging tool, means acting on the spindle for holding the tool in engagement with the valve with yielding force, means for oscillating the spindle, and a cam device and a projection engaging therewith, one of these being carried directly by the spindle for periodically moving the spindle longitudinally as it is being oscillated.
15. 6. In a valve grinding machine, the combination of a rotatable spindle carrying a valve-engaging tool, means acting upon the spindle to hold it in working engagement with the valve with yielding force, means for oscillating the spindle, a sleeve surrounding the spindle and having its edge
- formed into a cam, and a pin carried by the spindle and adapted to engage the edge of the said sleeve and to ride upon the said cam to cause longitudinal movement of the spindle as it is oscillated.
7. In a valve grinding machine, the combination of a rotatable spindle carrying a valve-engaging tool, means acting on the spindle for holding the tool in engagement with the valve with yielding force, a loosely supported sleeve surrounding the spindle and adapted to turn therewith and carrying a cam, a projection extending out from the spindle and adapted to rest upon the sleeve to cause it to turn with the spindle and also adapted to ride upon the cam to move the spindle longitudinally, and means for stopping the rotation of the sleeve with the spindle to cause the pin to traverse the cam.
8. In a valve grinding machine, the combination of a rotatable spindle carrying a valve-engaging tool, a spring acting upon the spindle for holding the tool in engagement with the valve with yielding force, means for oscillating the spindle, a sleeve loosely supported and surrounding the spindle provided on its edge with a cam and carrying a projecting lug, a projection carried by the spindle and adapted to engage with the edge of the sleeve and to ride upon the cam thereof, and a stationary stop with which the said lug of the sleeve engages, whereby its rotative movement with the spindle is arrested.

EARL CASNER.
